UNITED STATES PATENT OFFICE.

NOËL CHAUSSIER, OF PARIS, FRANCE.

AMUSEMENT AND RECREATIVE DEVICE FOR FAIRS AND THE LIKE.

Application filed August 13, 1927, Serial No. 212,780, and in France August 25, 1926.

The present invention relates to improved amusement and recreative devices or games for use at fairs, recreation parks and the like.

5 The principal object of the invention is to provide a device wherein a moveable member actuated by a player (i. e. a person playing at the game) operates on a member actuated by the impact of said moveable member 10 in such manner as to cause the simultaneous opening of the shutter of a photographic apparatus directed towards said player and the actuation of means for illuminating the latter, when said impact exceeds a certain 15 pre-determined limit.

The accompanying drawings show, by way of example, in Figs. 1 to 8 a preferred constructional form of the invention, in which the moveable member is adapted to 20 strike against a buffer or tappet and thus to cause the actuation of the illuminating means and of the photographic apparatus when the impact of the blow delivered by the moveable member on said buffer or tappet attains a certain magnitude, the force 25 of the blow being (other things being equal) a function of the speed impressed on the moveable member.

Referring to the drawings:

30 Fig. 1 shows the buffer or tappet device in front elevation.

Fig. 2 is a side view of the buffer or tappet device with some parts in cross section taken on line IX—IX of Fig. 1,

35 Fig. 3 shows the same device viewed from the back,

Fig. 4 shows the diagram of electrical connections of the said device,

40 Fig. 5 is a plan view to a smaller scale showing the arrangement of the two photographic apparatuses in an amusement device having two parallel paths with two buffers or tappets,

45 Fig. 6 shows in elevation the shutter of the lens of the photographic apparatus in the closed position,

Fig. 7 shows in elevation a modified arrangement of the shutter device illustrated in Fig. 6 connected to a common source of 50 electricity supply for operating the illuminating device and effecting the release of the shutter, and

Fig. 8 shows a side view of the shutter device for the photographic lens.

55 The reference numeral 38 denotes the path

or guide on which an impelled projectile (which is not shown on the drawing, but which may be of any desired form) rolls. The reference numeral 39 denotes a buffer or tappet which receives the blow of the projectile. Said buffer or tappet slides in a cylindrical guide 40 and is provided with a spring 41 tending to return it to its initial position. This spring provides the resistance which is registered on the dial 42. The 60 reference numeral 43 denotes a lever which oscillates around the axle 44 and is adapted to be pushed backward by the buffer 39. The lever 43 is likewise provided with a spring 45 which tends to return it to its initial position and which may also serve as a resistance.

The reference numeral 46 denotes a cable fixed at the end of the oscillating lever 43, which cable passes over rollers 47, is wound round the grooved pulley 48, and is connected 75 at its end to the fixed point 49 through the medium of a tension spring 50 adapted to cause the pulley 48 to rotate and thus to bring the pointer 51, which is rigidly fixed to said pulley, back to zero. This pointer 51 is actuated by the pulley 48 moving with regard to the dial 42 and forms a contact arm adapted to make contact with a contact 52 the position of which has been previously chosen.

The reference numeral 53 denotes a chamber for the production of strong light and the reference numeral 54 denotes the photographic apparatus trained on to the end of the projectile path near to which the player is situated.

80 The axle 55 of the pointer 51 is connected by means of a conductor 56 (Fig. 4) to one of the poles of an electric supply circuit.

One of the contacts 52 corresponding to a predetermined force of impact of the projectile against the buffer 39 and fixed in advance before the commencement of the game, is connected by means of two conductors 57—58 in parallel to the illuminating device in the chamber 53 and to the device for opening the shutter of the photographic apparatus 54 and from there to the other pole of the electric supply circuit.

90 The mode of operation of the apparatus thus constructed is as follows:—

100 The player estimates the force in kilogrammes with which he hopes to project the moveable member rolling on the rails 38 against the buffer 39. The proprietor of the amusement device connects the contact 52 110

corresponding to this force with the apparatuses 53 and 54 by means of a plug or a rotary switch.

The competitor then imparts a powerful impulse to the moveable body (not shown on the drawings) which ascends the incline 38 and, if the player is strong enough, strikes the buffer 39 at the end and pushes it inwards in its cylindrical guide 40. The buffer 39 pushes back the lever 43 which turns upon its pivot, pulls on the cable 46 and causes the pulley 48 and the pointer 51 to rotate. If the force exerted by the player has been sufficiently great, the said pointer comes into contact with the contact 52 and closes the electrical circuit indicated in Fig. 4. The current causes the production of the necessary illumination in the chamber 53, as also the opening of the shutter of the photographic apparatus and the player is photographed.

Referring to Figs. 6 to 8, the shutter proper consists of a member 24 provided at its upper part with an opening 25 serving to uncover the lens 26 when the photographic plate is to be exposed.

The member 24 is mounted on an axle 27 which oscillates freely in a bracket 28. The armature 29, which is rigidly connected to the member 24, terminates in arms 30 and 31 which are curved as indicated in Fig. 8 with a view to preventing their sticking on the cores of the electro-magnets 32 and 33.

The switch 34 which represents diagrammatically the switching device provided in the apparatus and serving to effect the photographing of the winning competitor closes for this purpose the circuit of the solenoid 33, the result of which is to cause the arm 31 to be strongly attracted at the precise moment when the opening 25 has uncovered the lens 26.

The metallic plate 34 has then put the two brushes 35 in connection with one another, whereby the circuit of the apparatus 36 for the production of artificial light has been closed. It will therefore be understood that as the lens has been uncovered, the competitor will have been photographed.

Fig. 7 shows the position of the shutter at the moment when the plate is exposed at the same time as the artificial light is produced, and Fig. 6 shows the shutter at the end of its travel when the artificial light has been extinguished and the lens covered again.

In order to set the shutter in position ready for use again, it is only necessary to close the switch 37 which may, for example, take the form of a push-button. When this is done the electro-magnet 32 will attract the arm 30, whereby the shutter 24 will be brought over into a position which is the reverse of that indicated in Fig. 6.

The artificial light may be produced by a flash-light powder or an electric illuminating source of any kind. The electrical energy necessary for the production of the light may be taken from a separate source or from the source of energy serving for operating the apparatus. It will be clear that relays may be employed for instance, in cases where the artificial light requires a large current, in order to avoid arcing on the automatic switching devices.

I claim:

1. A device for the amusement and recreation of the public, comprising in combination: a movable member adapted to be actuated by a person indulging in the recreation, a photographic apparatus trained on to the place of location of said person, an illuminating device likewise trained on to the said place of location, a buffer member adapted to be actuated by the impact of said movable member, and electric circuit adapted to be closed by said buffer member when actuated by an impact exceeding a predetermined value, and means associated with said electric circuit for causing simultaneously the opening of the shutter of said photographic apparatus and the actuation of said illuminating device for the purpose of illuminating and photographing said person when said electric circuit is closed.

2. A device for the amusement and recreation of the public, comprising in combination: a movable member adapted to be actuated by a person indulging in the recreation, a track for said movable member, a buffer arranged at the end of said track and adapted to be actuated by said movable member, a lever adapted to be oscillated by said buffer when the latter is struck by said movable member and the impact exceeds a predetermined value, a cable actuated by said lever against the action of a spring, a pulley upon which said cable is wound, a pointer adapted to be displaced by the movement of said pulley, an electric supply circuit, a graduated dial adapted to measure the displacements of said pointer by means of contacts which are arranged on said dial and co-operate with said pointer to close said electric supply circuit, an electro-magnet connected to said electric circuit, a photographic apparatus the shutter of which is controlled by said electro-magnet and which photographic apparatus is trained upon the place which would be occupied by a person indulging in the recreation, and a source of illumination actuated electrically by said electro-magnet simultaneously with the opening of the shutter of said photographic apparatus.

In testimony whereof I have signed my name to this specification.

NOËL CHAUSSIER.
